UNITED STATES PATENT OFFICE.

DOUGLAS MACCOLLUM STEWART, OF NEW YORK, N. Y.

SHADE HOLDER FOR CANDLES.

Application filed March 2, 1925. Serial No. 12,553.

This invention relates to shade holders for candles, and particularly to the type which will descend automatically as the candle is consumed in order that the flame 5 of the candle will at all times be properly positioned with respect to the shade.

Various attempts have been made to provide shade holders having such a property, but they have been open to numerous objections. For example, some of them, in descending, have a tendency to tip sidewise due to the melting of the wax or tallow more rapidly on one side than on the other and also due to the sticking of some part 15 of the same to a portion of the candle body, such as might be caused by some of the melted wax or tallow running down the candle body and freezing to the shade holder, and in such cases the shade is frequently tilted into the range of the flame 20 and scorched or burned. This is a fire hazard which is highly objectionable.

Difficulty has also been experienced in maintaining a level congealed wax ring at 25 the burning end of the candle body, which will prevent the melted candle body from running down the sides where it will be inaccessible for burning and perhaps congealing in a manner that might interfere 30 with the descent of the shade holder.

Other attempts have been made to support a shade and allow it to descend as the candle body is consumed, utilizing external poles or posts supported from the candle-stick 35 holder, but such devices are more or less unsightly and unattractive in appearance and do not always function properly during their descent, due to binding upon one post more than another.

An object of the invention is to provide 40 an improved shade holder for candles which may be readily adapted to fit candles of different diameters; which may be supported entirely by the candle and descend as the candle is consumed; which will permit of removal of the shade without removal 45 of the holder; which may be removed with the shade by the simple act of lifting the shade; which will always descend in a stable 50 condition as the candle is consumed; which will maintain a uniform peripheral wax ring for the crater of melted wax below the burning taper; with which loss of the melted wax by reason of its non-burning 55 will be prevented; which will automatically disengage itself from any protuberances of

congealed wax which may be formed or have congealed upon the body of the candle during use; which will prevent tilting of the shade into proximity to the flame; and 60 which will be free of all outside projections, posts or the like.

A further object is to provide an improved shade holder for accomplishing each or all of the above objects, separately and 65 collectively in various groups, and which will be simple, effective, durable, attractive in appearance and relatively inexpensive.

Various other objects and advantages will be apparent from the following description 70 of an embodiment of the invention, and the novel features will be particularly pointed out hereinafter in connection with the appended claims.

In the accompanying drawing:—

Fig. 1 is an elevation of a candle to which is applied a shade holder constructed in accordance with this invention, with the position of the shade illustrated in dot and dash lines;

Fig. 2 is a plan of the same;

Fig. 3 is a sectional elevation through a portion of the holder, the section being taken substantially along the line 3—3 of Fig. 2; and

Fig. 4 is a sectional plan through the same, with the section taken substantially along the line 4—4 of Fig. 1.

In the illustrated embodiment of the invention, the candle body 1, having a flame supporting taper 3, is supported in an upright position in a suitable base or holder 2, as usual heretofore. A short length of metal tubing 4, of greater diameter than the diameter of the candle body 1, is provided with a plurality of slits 5 extending longitudinally thereof from one end, so as to provide a plurality of arms 6 which extend partly the length of the tube. The arms 6 are drawn together and in progressively overlapping relation so as to give to the slotted end of the tube a frusto-conical portion uppermost and of less diameter than the diameter of the candle body.

This tube, as thus formed, is somewhat in the nature of a ring having a frusto-conical upper portion, as will be observed. When this tube is placed over the upper end of a candle body as shown in Fig. 1, the upwardly converging upper end will rest upon and be supported by the peripheral or marginal portion of the upper end of the candle

body. The lower end of the tube will, of course, diverge downwardly and terminate in the unslotted portion.

The overlapping of the arm 6 at the upper end reduces the diameter of the tube and provides small spaces such as grooves or valleys on the inner wall extending lengthwise of the candle body over the length of contact between the tube and candle. These grooves 5 pass air around the upper end of the candle and cool the wax or tallow around the edge of the burning end and thereby maintain a congealed rim to confine the melted wax. Thus the rim does not melt at one side more 10 than another, and the tube descends quite uniformly, and there is no opportunity for the melted wax to overflow, congeal, and interfere with the downward travel of the tube 4.

20 If any of the tallow or wax at the burning end does melt and reach the tube in such quantities that it cannot be restrained in the crater surrounding the taper, it can pass downwardly through the valleys or grooves 25 7 or, if in sufficient quantity to overflow, upon the outer surface of the tube where it will be guided to the base without coming in contact with the sides of the candle body to which it might freeze.

30 The unslotted or lower end of the tube 4 is provided, at a plurality of peripherally spaced points, with struck-out straps 8 which extend horizontally and with the body of the tube form pockets. Immediately below 35 the straps or pockets, integral tongues 9 depend from the lower end edge of the tube or ring to form pivot connections for a purpose to be explained presently. A plurality of prop members 10 are attached to the tube or ring 4 by means of such depending tongues 9, the members or props having apertures 11 through which the tongues 9 extend. The ends of the tongues 9 may be clinched upwardly as at 12, thereby confining the members 40 to the tongues while permitting a hinge-like movement between the members and the ring or tube 4.

45 Each member 10 terminates at its upper end in an extension or tongue 13 which extends into the pocket formed by the strap 8 above it, being confined in said pocket and against the outer face of the unslotted end of the ring with only sufficient play or clearance between it and the pocket walls to permit of a slight limited oscillation thereof upon the tube in a direction toward and from the candle body. The members 10 are preferably formed of strips of sheet metal, such as spring steel or brass, and depend downwardly and inwardly into engagement with the candle body where they are rolled backwardly as at 14 to form beads which engage with and run along the peripheral surface 50 of the candle body. The free end portions 55 of the members are extended upwardly and

outwardly as at 15 to form supporting arms, upon which the lower end of a shade 16 may rest, as shown in Fig. 1. The free ends of the portions 15 are bent upright as at 17, and then flanged radially and inwardly as 70 at 18, so as to engage or hook over a flange 19 provided upon the lower end of the shade 16.

The rolled or beaded portions 14 of the members which engage the candle body are 75 inclined to vertical planes that are tangent to the candle body at the points of contact. The inclination of all the members should be peripherally in the same direction, as shown in Fig. 4, so that if any member, during the 80 descent of the tube or ring 4, should engage with an irregularity or protuberance upon the side of the candle body, it will automatically be disengaged therefrom. The action with such a protuberance as might be caused 85 by the solidification of melted wax along the side of the candle, is of a camming effect in a horizontal direction, which rotates the tube until it is disengaged from the protuberance. This action takes place because of the fact 90 that all the portions 14 are horizontally inclined in the same direction, and it occurs even though more than one member 10 should encounter a protuberance.

95 In the use of the shade holder, it is supported upon the candle body 1, as shown in Fig. 1, with the converging end resting upon the upper end of the candle, so as to be supported thereby and descend therewith as the body of the candle is burned away. The 100 entire tube or ring 4 is out of contact with and spaced from the candle body except where the converging end rests upon the upper end portion of the candle, and at such contact the valleys or grooves 7 which are 105 formed by the overlapping of the arms 6 will permit of circulation of air upwardly through the tubes. This circulation of air will keep the peripheral portion of the upper end of the candle cool, so that a natural congealed but slowly descending wax rim will be produced as the support for the tube. The 110 tube may be drawn in or contracted at its upper end so as to fit candles of slightly different diameters.

115 Any fluid wax or tallow which tends to overflow the margin will either pass through the grooves 7 or, if in quantity, will pass over the outer surface of the tube 4, so as to be kept clear of the candle surface. The air 120 space between the arms at the point of overlap, and the fact that the tube is of metal, aided by additional circulation and by conduction of heat, results in keeping the tube and the upper end of the candle body cool 125 enough to support the holder.

130 The members 10, which are usually and preferably three in number, will ride along the sides of the candle and serve to keep the lower end of the tube or ring 4 spaced equally

on all sides from the candle. The shade 16 will rest upon the outwardly extending portions or arms 15 of the members 10, and the normal distance between the flanges 18 will be such that when a shade is resting on the members 10 at least one of the flanges 18 will engage over the flange 19 at the lower end of the shade. Then by reason of the small limited movement between the tongue 10 or extension 13 and the walls of the pocket formed by the strap 8, the shade, when lifted, will be automatically moved into engagement with the rest of the flanges 18 so that the holder will always be lifted with the shade. For example, when the shade is lifted, the particular flange 18 of the arm of the member 10 which is at that time hooked over the flange 19 will be lifted slightly without lifting the tube or ring 4, and during such movement the shade will automatically be shifted toward the other members 10 and into engagement with the other flanges 18, whereupon further lifting movement will cause a lifting of the tube or ring 4 from the candle.

If, for any reason, some of the fluid wax or tallow in the crater surrounding the burning taper should overflow, run down the side of the candle, engage the member and congeal and thus freeze the members to the candle, the holder will automatically disengage itself. Since the members have only a limited outward movement, the continued descent of the free members will cause a slight tilting of the tube 4 and by reason of the weight of the tube, the other member, which is frozen to the candle, will be moved away from the candle and thus broken loose therefrom.

If any member 10 engages a protuberance upon the candle that might interfere with its descent, it will be cammed horizontally until disengaged therefrom, by reason of the inclination of the contacting portion 14 to the plane which is tangent to the candle at the point of contact, as hereinbefore explained.

It will be observed that the center of gravity of the holder and shade is relatively low and, therefore, the shade and holder will be unusually stable in equilibrium, and there will be little tendency for the shade and holder to tip sideways. Furthermore, by reason of the limit to the movement between the members 10 and the tube or ring 4, provided by the pockets formed by the straps 8, there can never be sufficient tilting of the holder to carry the shade into or above the flame. It will also be noted that the tube or ring 4 is pulled, not pushed, downwardly, which is important in maintaining the shade in a stable condition.

Shade holders constructed in this manner will always descend in an upright condition, will never freeze or stick to the candle, or

tip the shade into position to be scorched, ignited, or injured by the flame. It presents an attractive appearance, since nearly the entire holder is concealed by the shade, and the shade will always be positioned in proper relation to the flame for the desired illumination, throughout the burning of the candle.

It will be obvious that various changes in the details, which have been herein described and illustrated for the purpose of explaining the nature of the invention, may be made by those skilled in the art within the principle and scope of the invention as expressed in the appended claims.

I claim:

1. A shade holder for candles, comprising an element engaging and descending with the upper burning end of the candle, a plurality of members connected to said element to depend therefrom, said members engaging with the candle body at spaced peripheral points of the latter and then extending outwardly to form supports for a shade, the portions of said members which engage the side of the candle body being inclined to planes tangent to the candle body at the points of contact and the inclination of all of said members corresponding in direction, whereby when any of said members engage protuberances upon the candle body, the said angle of inclination will serve during descent of the holder to cause a gradual rotation of the members and elements about the axis of the candle and free the members from the protuberances.

2. A shade holder for candles, comprising a metal tube of greater diameter than the candle body having slits extending longitudinally from one end and thus providing arms which are sprung together to reduce the diameter at the upper end to slightly less than the diameter of the candle body, whereby when the tube is placed over the upper end of a candle body the convergent upper end will rest upon and descend with the upper end of the candle, members connected to the lower unslotted end of said tube extending downwardly and inwardly to engage the candle body and having portions extending outwardly to form shade supports, whereby the center of gravity will be well below the points of contact between the tube and the candle body and the shade will be held against tipping by the engagement of said members with the candle body, the surfaces of said members engaging the candle body being inclined to planes which are tangent to the candle body at the points of contact, and the inclination for all of the arms corresponding in direction, whereby when any member engages a protuberance, it will be cammed peripherally of the candle body during the descent of the tube in order to free it laterally from the protuberance.

3. A shade holder for candles, comprising an element of sheet metal which rests upon and descends with the upper end of the candle body, the element having near its 5 lower end a plurality of peripherally spaced pockets and tongues depending beneath the pockets, and guiding and balancing members for said element formed of strips of sheet metal, each having an end passing 10 into a pocket and having an aperture through which the tongue below that pocket is passed to form a pivot connection, with the pocket walls of the element limiting the rocking movement of the member in a radial direction both outwardly and inwardly, the members having portions extending into contact with the candle body and also having portions extending outwardly to form shade supports. 15
- 20 4. A shade holder for candles, comprising an element of sheet metal which rests upon and descends with the upper end of the candle, the element having near its lower end a plurality of peripherally spaced struck-out straps forming pockets, and tongues depending beneath the straps, guiding members for said element formed of strips of sheet metal, each having an end passing 25 under a strap and having an aperture through which the tongue below the strap is passed to form a pivot connection, with the strap and body of the element limiting the rocking movement of the member in a radial direction both outwardly and inwardly, the members having portions extending into contact with the candle body 30 and also having portions extending outwardly to form shade supports, the portions of said members engaging with the candle body being inclined, in a horizontal direction, to planes which are tangent to the candle body at the points of contact, with the inclination of all corresponding in direction peripherally of the candle body, where- 35 by when one of the members engages an irregularity on the candle body, it will be cammed horizontally and peripherally of the candle body to free it therefrom by the descent of the element and members. 40
- 45 5. A shade holder for candles, comprising an element of sheet metal having a convergent upper end which rests upon and descends with the upper end of the candle, the element having near its lower end a plurality of pockets and tongues depending 50 beneath the pockets, guiding members for said element formed of strips of sheet metal, each having an end passing into a pocket and having an aperture through which the 55
- tongue below that pocket is passed to form a pivot connection, with the walls of the pocket limiting the rocking movement of the member in a radial direction both outwardly and inwardly, said members having portions extending into contact with the candle body and also having portions extending outwardly to form shade supports, the supporting portions of said members being flanged inwardly to engage a shade, whereby when the shade is lifted, the engagement of any flange of a member with the shade will automatically cause a movement of the other flanges into engagement with the shade during the lifting movement. 60
- 65 6. A shade holder for candles, comprising a thin metal tube having a plurality of slits extending longitudinally thereof from one end, the slotted end being reduced in diameter by causing an overlapping of the arms formed by the slits, whereby when the tube is placed upon the burning end of a candle the converging end will rest upon and descend with the burning end of the candle, means carried by the tube and riding along the sides of the candle body to prevent tipping of the tube to any material extent, the portions of said means which are engaging the candle body being inclined, in an approximately horizontal plane, to planes tangent to the candle body at the points 70 of contact, whereby said means will be automatically disengaged from any protuberance of the candle body encountered thereby by a lateral camming action upon the inclined portions during continued descent 75 of the tube. 80
- 85 7. A shade holder for candles, comprising an element engaging and descending with the upper burning under portion of the candle, a plurality of members carried by the element and running along the sides of the candle body to prevent tipping of said element beyond predetermined limits, the portions of said members engaging the candle being inclined in approximately a 90 horizontal plane to planes tangent to the candle body at the point of contact, whereby when any member engages a protuberance on the surface of the candle body, it will be automatically disengaged therefrom by a 95 horizontally camming action between such protuberance and the member encountering it, through the continued descent of said element. 100
- 105 In witness whereof, I hereunto subscribe my signature. 110
